(57) CLAIM

The ornamental design for a shoe, as shown and described.

DESCRIPTION

The file of this patent contains at least one drawing/photograph executed in color. Copies of this patent with color drawing(s)/photograph(s) will be provided by the Office upon request and payment of the necessary fee.

1. Shoe

1.1 : Front

1.2 : Back

1.3 : Perspective

1.4 : Right

1.5 : Left

1.6 : Top

1.7 : Bottom

Marks, wording and numbers shown in the original drawings have been deleted and instead, dashed line areas have been provided on the amended drawings to show that these marks, wording and numbers do not form part of the claimed invention.

1 Claim, 6 Drawing Sheets
